METHOD OF OBTAINING ELECTRON BEAM OF CONTROLLED LOW ENERGY

Richard E. Honig, Princeton, N. J., assignor to Socony Mobil Oil Company, Inc., a corporation of New York

Application December 12, 1951, Serial No. 261,337

4 Claims. (Cl. 313—78)

In many applications of electron physics, the production of mono-energetic electron beams of well-defined, low energies is of importance. All sources of electron beams presently known produce particles with initial energies ranging from zero to several electron volts, the distribution function often being Maxwellian. For example, of the electrons emitted by a tungsten filament run at 2500° K., 10% have initial energies in excess of 0.5 volt. Thus, in experimental work using low-energy electrons, such as the study of chemical reactions initiated by "controlled" electrons, the determination of critical potentials, the application of critical potentials to experimental and analytical processes, and the like, the thermal energies are of a magnitude too large to be neglected.

To reduce the distribution of thermal energies, energy filters have been used in the past that are based upon electric or magnetic fields, or on a combination of the two. In particular, the following schemes have proven useful:

1. Transverse magnetic filter—180°
2. Radial electrostatic filter—127°
3. High frequency, plane electrodynamic filter
4. Crossed transverse electrostatic and magnetic filter.

Of these four schemes, the first is the simplest and possibly the one most used. It is widely used in such instruments as the mass spectrometer. However, all of these are subject to one consideration. In all, the earth's magnetic field is present and acting and must be considered and controlled, eliminated, or overcome. The transverse magnetic filter type of operation requires an extended, homogeneous magnetic field of constant magnitude. To attempt to realize this by artificial means, at proper intensities for the production of electron beams of tightly controlled low energy and at the same time eliminate, control, or erase the effects of the earth's magnetic field is difficult.

This invention is based upon the realization that the earth's magnetic field is homogeneous over a practically limitless volume, that it is constant to within about 0.1% of its value over time periods relatively extended with respect to periods in which it will normally be utilized, and that its intensity is just right for the handling and analysis of electrons of a few volts of energy. This invention then, as may be seen from the drawings attached to and made a part of this specification, is essentially an electron analyzer in which the earth's magnetic field is used as a transverse magnetic filter, the source, path and slit elements of which are so mounted that they are capable of being brought into proper relationship with the geomagnetic field at the point and time of operation. In these drawings, Figure 1 is a schematic drawing of the instrument setup, and Figure 2 is a similarly schematic showing of a mount for same. Figure 3 shows a schematic electrical set-up of the instrument.

Turning now to Figure 1 of the drawings, 10 is a

2

filamentary source of electrons and 11 is a shell electrode having a directional slit 12 through which electrons are emitted in the desired direction. Split plate 13 serves to admit these electrons to the curved path 5 portion of the apparatus, housed in tube 14, in which the electrons describe a path of radius R, the magnitude of which is dependent upon the desired energy of electrons to be selected and upon the magnitude of the magnetic field F, which is the terrestrial magnetic field existing at the point and time of operation of the apparatus, the apparatus being so mounted as to be capable of positioning to bring the plane of the electron path normal to the direction of the geomagnetic field. At 15 we find a second slit plate and at 16 an electronically adjustable slit. The path R is housed in a metal tube, electrically integral with slits 13 and 15, providing an electrostatic shield, necessary to prevent the charge-up of glass walls with stray electrons. Vessel 17 serves to house the electron source and vessel 18 to house the process, instrument, or whatever item may be desired for a target of the selected electrons. Connections are provided at 19, 20, 21 for pumping out the various portions of the apparatus to the desired vacuum level, and it will be understood that whatever electrical leads, devices for reaction, targets, and the like are desired may be placed in vessel 18.

In Figure 2, highly schematic, it is shown how the device may be mounted to be placed in desired relation to the geomagnetic field. In its most simple form it 30 could be a support 22 for the device itself, mounted upon double swivels 23 and 24. In an elaborate form, it could be a servo-motor driven device of the character of an equatorial telescope mounting, electronically controlled to be held accurately in the geomagnetic field, 35 although the magnitude to time-direction variations of the geomagnetic field is ordinarily quite small.

Figure 3 shows a schematic electrical setup for the instrument, and to the right of it in the same figure, an ion collector and an electron trap which might be used 40 in case the electrons produced were to be used to ionize a gas contained in vessel 18. In this figure, the same members are used for the parts found in Figure 1. This figure is largely self-explanatory. In Figure 3, electrons are generated at 10, 11, passing out through orifice 12 and thence through "lens" orifices in 13, 15, and 16 at opposite extremities of the collimating tube 14, in which tube the electron is exposed only to the influence of the geomagnetic field. The emergent electrons, acting to ionize by bombardment a gas which is passed 45 through vessel 18 from entry 19 to exit 20, finally end their travel in electron trap 21. The ionization resulting from this bombardment of gas confined in 18 is detected by ion collector 22.

It will be understood, of course, that this instrument 55 should be shielded from magnetic fields other than geomagnetic, and that it is advisable, when it is in operation, to have datum plane observation of the time variations of the geomagnetic field. These features will partake of the nature of the shielding and base datum observation already developed and widely used in connection with magnetometers, used for oil prospecting by observations of variations in the geomagnetic field.

I claim:

1. Apparatus for producing a beam of monoenergetic low energy electrons comprising a source of electrons, collimating means to form a directed beam from at least some of the electrons emitted thereby, means to subject the beam therefrom to dispersion by the geomagnetic field in the substantial absence of other dispersion force, and a second collimating means to produce a monoenergetic electron beam from a selected portion of the

dispersed electrons, said second collimating means be so located as to collimate only that portion of the electron dispersion spectrum comprising electrons of the desired energy.

2. Apparatus for producing a beam of monoenergetic low energy electrons comprising a source of electrons, collimating means to form a directed beam from at least some of the electrons emitted thereby, means for directing the longitudinal axis of said collimating means into a plane normal to the geomagnetic field to permit dispersion of the electrons thereby, and a second collimating means to produce a monoenergetic electron beam from a selected portion of the dispersed electrons, said second collimating means be so located as to collimate only that portion of the electron dispersion spectrum comprising electrons of the desired energy.

3. Apparatus for producing a beam of monoenergetic low energy electrons comprising a source of electrons, collimating means to form a directed beam from at least some of the electrons emitted thereby, means for directing the longitudinal axis of said collimating means into a plane normal to the geomagnetic field to permit dispersion of the electrons thereby in accordance with their energies, and means to select and collimate dispersed electrons whose energies fall within a desired 25 range to form therefrom a monoenergetic electron beam of low energy.

4. Apparatus for producing a beam of monoenergetic low energy electrons comprising a source of electrons, collimating means to form a directed beam from at least some of the electrons emitted thereby, means for directing the longitudinal axis of said collimating means into a plane normal to the geomagnetic field and maintaining it in such position to permit dispersion of the electrons thereby in accordance with their energies, and a second collimating means to produce a monoenergetic 10 electron beam from a selected portion of the dispersed electrons comprising only electrons of the desired energy level.
